UNITED STATES PATENT OFFICE.

JOSEPH A. RAYDER, OF PHILADELPHIA, PENNSYLVANIA

AMPLIFIER.

Application filed May 3, 1924. Serial No. 710,886.

To all whom it may concern:

Be it known that I, JOSEPH A. RAYDER, a citizen of the United States, residing at Philadelphia, in the county of Philadelphia, Pennsylvania, have invented a new and useful Amplifier, of which the following is a specification.

This invention relates to amplifiers for sound reproducers, and it has more particular reference to that type of article now commonly known as a "loud speaker", the primary object being to provide a device of the character stated of exceptional capacity.

Another object is the attainment of better tonal reproduction, with incident elimination of local interference due to the prevailing vibratory influences associated with amplifiers as at present constructed.

A further object is to greatly clarify reproduction of the tonal effects and sounds emitted through my novel form of amplifier, by insulating the reproducing instrumentality completely from all surrounding metallic or other substances tending to mar and interfere with accurate tonal reproduction.

With the foregoing, and other objects in view, as will be apparent from the following description of practical embodiments of my invention, the same may be succinctly defined as consisting of an amplifying horn embodying a cellular wall and an insulating material base adapted to completely house the reproducing instrumentality.

In the further disclosure of this invention reference will be had to the accompanying sheets of explanatory drawings, wherein corresponding parts are designated by like indices in all the views.

Figure 1 is a sectional elevation of an amplifier or loud speaker conventionally embodying one form of my invention.

Figure 2 is a detail sectional view of an element comprised therein.

Figure 3 is a similar sectional detail of an opposed co-operating element.

Figure 4 is a sectional elevation of a slightly modified form of my invention; and,

Figure 5 is a sectional plan taken approximately on a plane as indicated by the arrowed line 5-5 shown on the preceding figure.

Referring more particularly to the drawings it will be observed that the amplifying

horn—per se—comprises two main parts comprehensively designated by the numerals 6, 7, the former of which is of standard goose-neck configuration while the latter is an outwardly diverging flare embodying concentric spaced walls 8, 9, affording a surrounding annular air or vacuum space 10. The outer wall section 8 is inwardly beaded at 11, to afford a seat for the outwardly flanged end 12 of the inner section 9, with interposition of a resilient U-section gasket 13, whereby an air tight joint is established. Similarly the inner end of the outer section 8 is shouldered and reduced to provide a seat 14 for the inner end of the inner section 9, with an intervening U-shaped gasket 15, to afford a tight joint thereat. The flared section or part 7, is made of thin sheet material, and it is adapted for coupling connection, to the goose-neck 6, by any convenient form of attaching means, such as thumb-screws 16. Incidentally, it is to be particularly noted, that, although I have shown and described the flaring section 7 only, as of cellular formation to provide the air or vacuum space 10, it is to be clearly understood that the goose-neck portion 6 may be similarly constructed.

To afford support for the amplifier constructed as above set forth, I make use of a glass, porcelain, or other appropriate insulate material base 17, having a concentric neck 18, in which the lower end of the goose-neck 6 is adapted to frictionally fit and seat thereon by means of an integral, or other, collar 19. The reproducing instrumentality or instrumentalities 20, is, or are, surrounded by, and seat within, cork or other suitable material cups 21, fitted with in complementary cells provided for their reception in a glass, porcelain or other appropriate insulate material open top box 22. This open top box 22, is closed in by a composite cover including an inner member 23, and an outer cap piece 24, the latter being provided at its upper part with a lateral flange 25, adapted to seat on a complementary shoulder 26 provided for the purpose in the neck 18 aforesaid.

The opposed or meeting faces of the two parts 23, 24, comprising the composite cover for the open top box 22, are fashioned with opposed recessions that, when said parts are assembled constitute spiral ducts 27, 27, one leading upwardly from each reproducing instrumentality 20 by an aperture 28 in the

inner section 23, and both merging into the common outlet 29, concentric with the abutting end of the goose-neck 6. In the drawings, the reproducing instrumentalities 20, 5 20 conventionally represent ordinary earphones of standard pattern, as I have found that they give excellent results, although it will be obvious any other suitable device may be employed. It is also to be observed 10 that the open-top box 21, composite cover, and insulate base 17, are rigidly clamped together—in separable relation—by a bayonet or other lock means, conventionally shown at 30; such manner of locking the respective parts together being readily comprehended by those conversant with the art, and needing no further explanation. It is, however, desired to particularly emphasize 15 the novel construction of amplifier supporting base 17 with the associated parts 23, 24, affording spiral outlets for the sounds reproduced by the instrumentality or instrumentalities 20, which are effectively insulated from local interference by the open- 20 top box 22.

Referring now to Figures 4 and 5, all such parts as generally conform with the preceding description are designated by the same distinguishing characters, and the following outline will, accordingly, be limited to the salient features of novelty. In the first place it will be noticeable that the open-top box 22, is closed-in by a single piece cover 31 having a series of radial projections 32, 30 adapted for passage through complementally configured notches 33, and by a partial turn to effect locking connection with the intervening segmental shoulders 34, provided for the purpose in the neck 18, of the base 17. In connection with this form of my invention, I employ a dished perforate distributor 35, having a screw-threaded shank 36, for adjustable engagement in the wall of the goose-neck 6, and rigid clamping 40 by lock nuts 37. This distributor 35, it will be seen, is perimetrically tessellated, each tessellation 38 having the inner end of a wire or string 39, attached thereto, and the outer or free end of each said wire is coupled to 45 an adjusting key 40 afforded bearing in the flare bead 11, as will be readily understood by an examination of the drawings. It will, of course, be understood that the adjusting keys 40 afford means whereby all 50 the respective wires or strings 40 may be attuned to the same pitch, and that said strings or wires function to distribute the sounds reproduced evenly around the amplifier flare 7.

55 Obviously, detail changes in the several parts may be readily effected without departing from the spirit of my invention,

therefore the right is hereby reserved to make all such reasonable modifications therein as fairly lie within the scope of the 65 appended claims.

Having described my invention what I claim is:—

1. An amplifier embodying a cellular walled horn and an insulate material base, 70 said base affording attachment for a reproducing instrumentality enclosure, and a cover for the enclosure having a spiralized passage communicating with the aforesaid horn. 75

2. An amplifier embodying a goose-neck and attached flare, the latter including concentric spaced members affording an annular interspace, packing means ensuring an air tight joint between the spaced members, 80 an insulate material base for the goose-neck, and a reproducing instrumentality insulating casing removably connected into the base. 85

3. An amplifier embodying a goose-neck 85 and attached flare, the latter including concentric spaced members affording an annular interspace, packing means ensuring an air tight joint between the spaced members, 90 an insulate material base for the goose-neck, a like material reproducing instrumentality—removably attached into the base and having a composite cover affording spiralized conduits between said instrumentality and the goose-neck. 95

4. In combination, an amplifier having a cellular wall, and an insulate material base removably attached thereto, said base including a reproducing instrumentality enclosure having a cover affording spiralized sound conduction orifices intermediate the reproducer and amplifier. 100

5. The combination with an amplifier of a base affording attachment for a reproducing instrumentality enclosure, having a 105 spiralized sound conducting passage communicating with the amplifier.

6. The combination with an amplifier of a base affording attachment for a reproducing instrumentality enclosure, and a cover for the enclosure having a spiralized sound conduction passage communicating into the amplifier. 110

7. In combination, an amplifier, an insulate material base therefor, a reproducing instrumentality enclosure removably attached within said base and having a spiralized sound conduction orifice connecting into the amplifier, and strings disposed around the inner surface of the amplifier 115 120 with capacity for adjustment.

In testimony whereof I affix my signature the 25th day of April, 1924.

JOSEPH A. RAYDER.
